US00D973621S

(12) **United States Design Patent** (10) **Patent No.:** **US D973,621 S**
(45) **Date of Patent:** **** Dec. 27, 2022**

(54) **MOBILE PHONE**

(71) Applicant: **BEIJING XIAOMI MOBILE SOFTWARE CO., LTD.**, Beijing (CN)

(72) Inventors: **Yake Hao**, Beijing (CN); **Wei Fang**, Beijing (CN); **Shengyu Gong**, Beijing (CN); **Xu Wei**, Beijing (CN); **Yin Zhu**, Beijing (CN)

(73) Assignee: **Beijing Xiaomi Mobile Software Co., Ltd.**, Beijing (CN)

(**) Term: **15 Years**

(21) Appl. No.: **35/512,419**

(22) Filed: **Feb. 26, 2021**

(80) **Hague Agreement Data**

Int. Filing Date: **Feb. 26, 2021**

Int. Reg. No.: **DM/213601**

Int. Reg. Date: **Feb. 26, 2021**

Int. Reg. Pub. Date: **Aug. 27, 2021**

(30) **Foreign Application Priority Data**

Sep. 1, 2020 (CN) 202030510400.3

(51) **LOC (13) Cl.** **14-03**

(52) **U.S. Cl.**

USPC ..... **D14/138 G**

(57) **CLAIM**

The ornamental design for a mobile phone, as shown and described.

DESCRIPTION

1. Mobile phone
  2. Mobile phone
  3. Mobile phone
  4. Mobile phone
- 1.1 : Front
1.2 : Back
1.3 : Left
1.4 : Right
1.5 : Top
1.6 : Bottom
1.7 : Perspective
1.8 : Perspective
1.9 : Partial enlarged view
2.1 : Front
2.2 : Back
2.3 : Left
2.4 : Right
2.5 : Top
2.6 : Bottom
2.7 : Perspective
2.8 : Perspective

(Continued)

2.9 : Partial enlarged view

3.1 : Front

3.2 : Back

3.3 : Left

3.4 : Right

3.5 : Top

3.6 : Bottom

3.7 : Perspective

3.8 : Perspective

4.1 : Front

4.2 : Back

4.3 : Left

4.4 : Right

4.5 : Top

4.6 : Bottom

4.7 : Perspective

4.8 : Perspective

Reproductions **1.1-1.8**, **2.1-2.8**, **3.1-3.8**, **4.1-4.8** are orthographic projection views and perspective views of mobile phones, respectively; reproduction **1.9** is a partial enlarged view of portion "A" in reproduction **1.7**; reproduction **2.9** is a partial enlarged view of portion "B" in reproduction **2.7**; the squares and letters "A" and "B" in reproductions **1.7** and **2.7** indicate the enlarged portions shown in reproductions **1.9** and **2.9** only and do not form part of the claimed designs.

1 Claim, 34 Drawing Sheets
